CLAIM

The ornamental design for a body for cooking machine, as shown and described.

DESCRIPTION

1. Body for cooking machine

1.1 Front

1.2 Back

1.3 Left

1.4 Right

1.5 Top

1.6 Bottom

1.7 Perspective

The broken lines shown in reproductions 1.5 and 1.6 depict portions of the body for cooking machine form no part of the claimed design.

1 Claim, 7 Drawing Sheets
